Attorneys.

UNITED STATES PATENT OFFICE.

WALTER I. WELLMAN AND JAMES M. DUNN, OF GARDEN CITY, KANSAS.

AUTO SCREEN.

Application filed December 20, 1926. Serial No. 155,942.

The present invention relates to screens and more particularly screens especially designed for use in connection with doors and windows of closed vehicle bodies.

5 An important object of the invention is to provide a screen which may be positioned within a window or door frame, so that the same will close the opening excluding foreign matter from the interior of the car, due consideration being had for the ventilation of the interior of the car.

10 Another object of the invention is to provide a screen of this character wherein the frame is constructed of flexible metal to the 15 end that the screen may be bent in such a way as to permit it to be positioned in the window guides of the window frame so that when the screen frame is released, it will automatically assume a position in close engagement with 20 the guides to hold the screen frame in position.

25 A still further object of the invention is to provide an operating mechanism whereby the screening idea may be carried out in such a way that the screen may become a permanent part of the vehicle structure to be raised and lowered at the will of the operator.

With the foregoing and other objects in view which will appear as the description proceeds, 30 the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view illustrating 40 a screen frame as positioned within the guides of a window and illustrating the operating means.

Figure 2 is a sectional view taken on line 2-2 of Figure 1.

45 Figure 3 is an enlarged sectional view showing the connection between the operating arm and screen frame.

Referring to the drawings in detail, the reference character 5 indicates a door or window frame of a closed motor vehicle body, which is provided with the usual lateral guides indicated at 6 and the well 7 in which the usual window moves.

In the present showing, the screen frame which is indicated generally by the reference character 8 is formed of sheet metal, the same being bent upon itself to clamp the wire mesh material of which the screen is formed, therebetween, in a manner as shown by Figure 3, the wire mesh material being indicated by the reference character 9.

A bar such as indicated at 10 is secured along the lower edge of the bottom of the screen frame, the same being provided with an elongated opening 11 in which the pin 12, 65 that extends laterally from the operating arm 13 moves. This arm 13 is of a length each that when the screen is in its closed or active position, the bar will be supported in a vertical position to properly support the weight 70 of the screen.

An enlargement indicated at 14 is formed at one end of the arm 13, the same being provided with teeth defining a segmental gear, meshing with the teeth 15 of the gear 16 mounted 75 on one end of the horizontal shaft 17 supported within the well 7, at the bottom thereof.

Bearings indicated at 18 provide the support for the shaft 17, and provide means whereby the shaft may be rotated with the 80 minimum amount of exertion on the part of the operator.

At the inner end of the shaft 17 is a substantially small gear 19 that meshes with the larger gear 20 mounted on the inner end of 85 the shaft 21 that carries the finger piece 22 at its outer end, the shaft 21 being shown as extending through one wall of the well 7.

Positioned within the well is a plate 23 that carries a laterally extended shaft 24 providing the pivot for the arm 13.

From the foregoing it will be seen that due to this construction, a person may by operating the finger piece 22, raise the screen to a position as shown by Figure 1 to close 95 the opening which has been made by moving the usual window of the vehicle, the window being indicated by the reference character 25, to its closed position.

We claim:

In a movable screen frame having a bar secured along its lower edge and having an elongated opening formed therein, an operating device including bearings, a horizontal shaft supported in the bearings, a small gear 100 on one end of the shaft and a large gear 105 on

the opposite end of the shaft, an operating shaft, a large gear mounted on the inner end of the last mentioned shaft and meshing with the small gear, a pivoted arm, a segmental gear on one end of the arm and meshing with the first mentioned large gear, said gears adapted to operate to swing the arm upwardly, and a right angled pin at one end of the

arm and movable in the elongated opening to move the screen frame to its active or inactive 10 position.

In testimony that we claim the foregoing as our own, we have hereto affixed our signatures.

WALTER I. WELLMAN.
JAMES M. DUNN.
